HOLDER FOR FLOWERS OR THE LIKE

James W. Yates, 45—665 Halekou Place,
Kaneohe, Hawaii 96744

Filed July 2, 1969, Ser. No. 18,029

Term of patent 14 years

Int. Cl. D11—99

U.S. Cl. D45—10

FIG. 1.

FIG. 2.

FIG. 3.

FIG. 5.

FIG. 4.

FIG. 7.

FIG. 8.

FIG. 6.

FIG. 1 is a perspective view of a holder for flowers or the like embodying my new design;

FIG. 2 is a front elevational view;

FIG. 3 is a top plan view;

FIG. 4 is a side elevational view;

FIG. 5 is a front elevational view of a holder for flowers or the like showing another form of my new design;

FIG. 6 is a top plan view thereof;

FIG. 7 is a top plan view of a holder for flowers or the like showing a third form of my new design; and

FIG. 8 is a top plan view of a holder for flowers or the like showing a fourth form of my new design.

I claim:

The ornamental design for a holder for flowers or the like, as shown and described.
